UNITED STATES PATENT OFFICE.

FRANK HIDI, OF GARWOOD, NEW JERSEY.

TABLE ATTACHMENT FOR BEDS.

Application filed August 21, 1924. Serial No. 733,367.

To all whom it may concern:

Be it known that I, FRANK HIDI, a citizen of the United States, residing at Garwood, in the county of Union and State 5 of New Jersey, have invented certain new and useful Improvements in Table Attachments for Beds, of which the following is a specification.

This invention relates to certain new and 10 useful improvements in table attachments for beds wherein pivotally connected bracket arms mounted upon the corner post of a bed support a table top in a manner to permit the same to be disposed above the 15 bed.

A further object of the invention is to provide a table attachment for beds wherein the table top or platform is adjustably mounted longitudinally of a supporting 20 bracket arm for varying the positions thereof relative to the bracket arm to better accommodate the disposition of the table top relative to a person in the bed.

With the above general objects in view 25 and others that will become apparent as the nature of the invention is better understood, the same consists of the novel form, combination and arrangement of parts hereinafter more fully described, shown in 30 the accompanying drawings and claimed.

In the drawings, wherein like reference characters designate corresponding parts throughout the several views,

Figure 1 is a top plan view of the table 35 attachment for beds constructed in accordance with the present invention, a portion of the bed frame being illustrated,

Figure 2 is a side elevational view of the same,

Figure 3 is an edge elevational view of 40 the table attachment and a portion of the bedstead with the table attachment in its folded inoperative position,

Figure 4 is a fragmentary bottom plan 45 view of the table top,

Figure 5 is a detail sectional view taken on line V—V of Fig. 1 showing the adjustable mounting for the table top upon the bracket supporting arm,

Figure 6 is a detail sectional view taken 50 on line VI—VI of Fig. 5,

Figure 7 is a fragmentary side elevational view, partly in section showing the pivotal mounting for the main bracket supporting arm of the table attachment, and

Figure 8 is a detail sectional view show-

ing the tensioned latch pin connection between the pivoted ends of the supporting bracket arm.

Referring more in detail to the accompanying drawings there is illustrated a table attachment for beds wherein a bracket arm 1 is pivotally mounted as at 2 between the side straps of the clamping bracket 3 that is mounted upon the corner post 4 60 of a bedstead. The pivotal mounting of the bracket arm 1 is shown in detail in Fig. 7, the upper inner edge thereof being cut away between the side strap portions of the clamping bracket to form a 70 socket 5 that receives the cross pin 6 extending between the opposite sides of the clamping bracket, the pin 6 retaining the bracket arm 1 in a horizontal position when the same is lowered as illustrated. 75

A table top supporting bracket arm 7 is pivotally connected by the pin 8 to the outer end of the bracket arm 1 as shown in Figs. 1 and 8 and to retain the bracket arm 7 in adjusted position relative to the bracket 80 arm 1 against accidental movements, the pin 9 spring pressed as at 10 and carried by the bracket arm 1 is provided for selective reception in the circular series of depressions 11 formed in the opposed contacting face of 85 the bracket arm 7. The two bracket arms are preferably of rectangular configuration in cross-section, and the free end of the bracket arm 7 is of cylindrical formation as at 12 and shown in Figs. 5 and 6 with the 90 cylindrical end thereof provided with a longitudinal socket and internally threaded at 13.

The table top 14 is provided with depending spaced ribs 15, 16 and 17, the end rib 95 15 flatly engaging the upper face of the bracket arm 7 while the depending rib 16 is provided with an opening 18 to permit free passage of the cylindrical end 12 of the bracket arm 7. An adjusting screw 19 has 100 a plain portion that is rotatable in the opening 20 in the depending rib 17 and is retained against longitudinal shifting movement relative to the rib and table top by the securing collars 21 shown in Fig. 5. The 105 outer end of the screw 19 is provided with a finger piece 22 while the screw rod is threaded into the socket 13 of the bracket arm 7.

From the above detail description of the 110 device, it is believed that the construction and operation thereof will at once be ap-

parent, it being noted that by adjusting the screw 19, the table top 14 may be shifted longitudinally of the bracket arm 7 to more conveniently position the same relative to a person in the bed while further adjustiments of the table top are accomplished by the pivotal connection between the bracket arms 1 and 7. When the table attachment is out of use as illustrated in Fig. 3, the same is folded to assume an upright position adjacent the corner post of the bed, and when the same is lowered to its operative position, the notch portion 5 of the bracket arm 1 will receive the pin 6.

15 While there is herein shown and described the preferred embodiment of the present invention, it is nevertheless to be understood that minor changes may be made therein without departing from the spirit and scope 20 of the invention as claimed.

What is claimed as new is:—

1. In a table attachment for beds, a pair of bracket arms pivoted together at their ends, movement arresting means for the 25 pivotal connection, a clamping bracket secured to the bed, a pivotal connection between the free end of one bracket arm and the clamping bracket, a table top slidably mounted on the free end of the other bracket 30 arm, manually operable means for shifting the table top on the bracket arm, and a stop pin carried by the clamping bracket adapted to be engaged by the bracket arm pivoted

therein for holding the bracket arm in horizontal position.

2. In a table attachment for beds, a pair of bracket arms pivoted together at their ends, movement arresting means for the pivotal connection, a clamping bracket secured to the bed, a pivotal connection between the free end of one bracket arm and the clamping bracket, a table top slidably mounted on the free end of the other bracket arm, a screw swivelled to the table top and threaded into the associated bracket arm for shifting the table top thereon, and a stop pin carried by the clamping bracket adapted to be engaged by the bracket arm pivoted 45 therein for holding the bracket arm in horizontal position.

3. In a table attachment for beds, a pair of bracket arms pivoted together at their ends, movement arresting means for the pivotal connection, a clamping bracket secured to the bed, a pivotal connection between the free end of one bracket arm and the clamping bracket, a table top slidably mounted on the free end of the other bracket arm, and manually operable means for shifting the table top on the bracket arm, the 55 mounting of the table top further including a depending apertured rib slidable on the bracket arm.

In testimony whereof I affix my signature.

FRANK HIDI.
